DESIGN FOR A BUCKLE

Emanuel M. Meyer and David Levin,
New York, N. Y.

Application April 22, 1936, Serial No. 62,248

Term of patent 3½ years

To all whom it may concern:

Be it known that we, Emanuel M. Meyer and David Levin, citizens of the United States of America, residing respectively in city, county, and State of New York, and city, county, and State of New York, have invented a new, original, and ornamental Design for a Buckle, of which the following is a specification, reference being had to the accompanying drawing, forming part thereof.

Fig. 1 is a perspective view of a buckle showing my new design.

Fig. 2 is a plan view of a buckle as shown in Fig. 1.

We claim:

The ornamental design for a buckle substantially as shown.

EMANUEL M. MEYER.
DAVID LEVIN.
